(57) CLAIM

The ornamental design for a handle with blade as shown and described.

DESCRIPTION

FIG. 1 is a perspective view of a handle with blade; FIG. 2 is a top plan view of the handle with blade; FIG. 3 is a right side elevation view of the handle with blade, the left side elevation view of the handle with blade being a mirror image thereof;

FIG. 4 is a bottom plan view of the handle with blade; FIG. 5 is a rear elevation view of the handle with blade; and, FIG. 6 is a front elevation view of the handle with blade. The broken lines in the figures show environmental subject matter that forms no part of the claimed design.

1 Claim, 3 Drawing Sheets
